PROTECTIVE HELMET

George J. Hayes, San Antonio, Tex., and George M. Stewart, Bel Air, Md., assignors to the United States of America as represented by the Secretary of the Army

Continuation of abandoned design application Ser. No. 160,988, July 8, 1971. This application June 7, 1973, Ser. No. 367,930

Term of patent 3½ years

Int. Cl. D2—03

U.S. Cl. D2—231

Fig. 1.

Fig. 2.

Fig. 3.

Fig. 4.

FIG. 1 is a front elevational view of a protective helmet showing our new design;

FIG. 2 is a side elevational view thereof;

FIG. 3 is a rear elevational view; and

FIG. 4 is a top plan view.

The side not shown is substantially like the side shown.

This is a continuation of application Ser. No. 160,988, filed July 8, 1971 and now abandoned.

We claim:

The ornamental design for a protective helmet, as shown and described.
